DEVICE FOR TREATING SPINAL COLUMNS

Siegfried Peter Ulrich, Zurich, Switzerland

Application July 23, 1951, Serial No. 238,109

7 Claims. (Cl. 128—75)

1

The present invention relates to a device for extending the spinal column. Various experiments carried out in the past have shown that the strength of the spine increases from the cervical vertebra towards the lumbar vertebra, whilst the connection between the lumbar section and the sacrum, again, is considerably weaker. It is therefore clear that on the application of linear tension, which is effected clinically by an extensor, to the vertebral column, the weakest part thereof is expanded, whilst the central portion, which is strongest, remains unaffected. The history of extension treatment shows that these circumstances, and more particularly the greater tensile resistance of the spinal column in the lumbar region, have hitherto been insufficiently allowed for in practice. Yet it is evident that, on neurosurgical grounds, extension is desirable precisely in the lumbar section. The problem of the extension of the lumbar section of the spine is solved by the inventive construction, the principle of which is based not only on linear extension, but also on flexion of the lumbar section.

In the annexed drawing an embodiment of the invention is shown in a perspective view.

On a base 1, two jaws 3 and 4 are mounted by means of struts 2. Jaw 3 is fixed, whilst jaw 4 is mounted on a carriage 5 which can be moved to and fro by means of a spindle rotatable by a hand crank 6. An arm 7, which carries a cushion or pad 8 to support the head of the subject, is secured to the struts 2. On the base 1 a carriage 10 is so mounted in guides 11 as to be slidable in the longitudinal direction of the device. The sliding displacement is effected by means of a handwheel 12. A slide 13 arranged on the carriage 10 is capable of sliding displacement in the direction transversal to the movement of the carriage and is guided in guideways 14 provided on the carriage. Displacement of the slide 13 is effected by turning a handwheel 13a. Two gripping jaws 15, between which a ball 16 is arranged, are secured to the slide 13. Said ball carries a bracket 16a at the respective ends of which are provided a fixed jaw 17 and a jaw 18 slidable to and fro in relation to said fixed jaw 17. Adjustment of the jaw 18 is effected through a spindle 19 with the aid of a hand crank 20. Also rigidly secured to the bracket 16a is a frame 21 in which two rails 22 are so mounted as to pivot independently of each other. By means of arms 23, each rail can be fixed at any desired angle of inclination. By means of a screwed spindle 25 provided with a

2

crank 24, the ball 16 can be clamped fast between the clamping jaws 15.

Mounted on the slide 13, between the two pairs of jaws 3, 4 and 17, 18, is a support 26, adjustable for height, and carrying an interchangeable pad 27. The pad is always selected of a size appropriate to the circumstances of the moment. It would also be possible to arrange a plurality of pads on the support 26.

10 In order to perform, for instance, the straight leg bending test (Lasègue), the subject's body is fixed under the shoulders by the jaws 3, 4, whilst the jaws 17 and 18 fix the spina iliaca of the pelvis. The pelvis then rests, together with its 15 clamping jaws 17 and 18, on the ball-and-socket joint 15, 16, which, owing to the displaceability both of the carriage 10 and of the slide 13, can be shifted both in the longitudinal direction and sideways. It would also be possible to mount the jaws 17 and 18 in such a way as to be also 20 adjustable for height. The pivotal point of this ball-and-socket joint lies almost directly under the pelvis. The pad 27, likewise adjustable in any desired direction, then presses on the apex 25 of the desired point of the lumbar section, the corresponding inclination of the pelvis in any desired direction being obtainable by means of the ball-and-socket joint. In order to enable the flexing of the lumbar section to take effect over a greater distance, various attachments for the pad are provided, as already mentioned. In conjunction with the fixation of the pelvis, the two rails 22, which are hinged independently of each other, serve to bring the lower extremities into the necessary positions. Through one-sided elevation of the rails it is possible to carry out the straight leg bending test (Lasègue) or its various modifications.

40 Turning now to the technique of extension, the patient is first accurately fixed by the jaws 3, 4, 17, 18. Exact adaptation of the distance between the two pairs of jaws to the torso is obtained by linear displacement of the carriage 10 by means of the handwheel 12. By means 45 of the two hand cranks 6 and 20, the appurtenant jaws are applied accurately to the upper body and the pelvis respectively. Thereupon the pad 27 is set below the apex of the desired flexion of the lumbar section. Thereupon a pain is provoked by the straight arm bend test (Laseguian Experiment) by elevating the leg rails. With this, the preparations for extension are completed.

50 Experimentally, the pelvis is now adjusted on the ball-and-socket joint 6 until freedom from

pain is achieved by the appropriate flexing of the lumbar vertebrae. This position is then fixed by tightening the crank 24 and thereby clamping the ball 16. In this position it is now possible, if desired or necessary, to obtain a supplementary linear tension by turning the handwheel 12. For scientific work, the device can be equipped with a variety of measuring instruments to enable the extension to be measured. Thus, for instance, the linear tension can be ascertained by means of a spring balance, the angle of inclination of the pelvis by a plumbline, the elevation of the legs by a graduated scale, and the pressure of the spine on the pad by a tensiometer.

The inventive device can also be used for roentgenography and for spinal operations, and also for diagnostic and therapeutic purposes. The device enables precise extension, hitherto not possible, of the spinal column to be obtained at any desired point, and also enables the amount of such extension to be precisely determined at any time.

What I claim is:

1. In a device of the nature described for treatment of the spinal column; a frame, a first pair of jaw elements on the frame adjustable laterally relative to each other to grip a patient in the region of the shoulder, a second pair of jaw elements spaced longitudinally from the first pair of jaw elements operable for substantially rigidly gripping a patient in the pelvic region and also laterally adjustable relative to each other, a slide on the frame beneath said second pair of jaws adjustable longitudinally and laterally of the frame, one part of a ball-and-socket joint on said slide and the other part on said second pair of jaw elements for swivelly supporting the second pair of jaw elements on this slide, said pairs of jaw elements being elevated above said frame so that a patient's body will hang free therebetween, a supporting post rising upwardly from said slide between the said pairs of jaw elements, said post being vertically adjustable, and a pad removably mounted on the upper end of said post to supportingly engage a limited area of the patient's spine in the lumbar region.

2. In an arrangement as set forth in claim 1, in which means are provided for locking the said parts of said ball-and-socket joint together in any desired position of adjustability.

3. In an arrangement as set forth in claim 1, including straight leg boards extending longitudinally from the side of the second pair of jaw elements opposite the first pair of jaw elements, said leg boards being pivotally connected with said second pair of jaw elements for swinging movements in a vertical plane.

4. In an arrangement as called for in claim 2, including straight leg boards extending longitudinally from the side of the second pair of jaw elements opposite the first pair of jaw elements, said leg boards being pivotally connected with said second pair of jaw elements for swinging movements in a vertical plane.

5. In an arrangement as set forth in claim 3, including means for locking the said leg boards in any desired position of respective adjustment thereof.

6. In an arrangement as set forth in claim 4, including means for locking the said leg boards in any desired position of respective adjustment thereof.

7. In a device for the extension of the vertebral column; two pairs of spaced jaws for gripping the body of a patient in the shoulder region and in the pelvic region, said pairs of jaws being adjustable relative to each other and the body of the patient being unsupported between the jaws, a universally adjustable ball and socket joint supporting the pair of jaws for gripping the patient in the pelvic region, a vertically extending supporting column positioned between said pairs of jaws, means on said device to vertically adjust said column, and a padded upper portion detachably mounted on the upper end of said column, said upper portion being universally adjustable.
